UNITED STATES PATENT OFFICE

152,552

DESIGN FOR A CANDLE HOLDER

William E. Mackelfresh, Jr., Chicago, Ill.

Application December 26, 1947, Serial No. 143,371

Term of patent 3½ years

(Cl. D48—2)

To all whom it may concern:

Be it known that I, William E. Mackelfresh, Jr., a citizen of the United States, residing at Chicago, in the county of Cook and State of Illinois, have invented a new, original, and ornamental Design for Candle Holder, of which the following is a specification, reference being had to the accompanying drawing, forming part thereof.

I claim:

The ornamental design for a candle holder, as shown.

WILLIAM E. MACKELFRESH, JR.
